ATTORNEY.

UNITED STATES PATENT OFFICE.

MANUEL CORREIA, OF NEW BEDFORD, MASSACHUSETTS.

CURTAIN HOLDER.

Application filed February 9, 1928. Serial No. 253,107.

This invention relates to certain new and useful improvements in curtain holders, and has more particular reference to an improved device for holding the lower portions of curtains and similar draperies in backwardly drawn condition at the sides of door or window frames.

The primary object of the present invention is to provide an improved device or curtain holder of the above kind which may be conveniently and effectively secured to a door or window frame without the use of nails, screws and similar fastening devices.

A further object is to provide a curtain holder which is adjustable for ready application to side door or window frame members of varying or different widths, and which embodies correspondingly adjustable curtain engaging elements for proper engagement with and holding of the curtains in drawn back condition.

A still further object is to provide a curtain holder of the above kind which is extremely simple and durable in construction as well as efficient in use, and which embodies improved curtain engaging elements with which the curtains may be readily engaged or from which the curtains may be readily disengaged.

Other objects will appear as the nature of the invention is better understood, and the same consists in the novel form, combination and arrangement of parts hereinafter more fully described, shown in the accompanying drawing and claimed.

35 In the drawing:—

Figure 1 is an elevational view of a double window frame having curtains held in backwardly drawn condition by means of curtain holders embodying the present invention;

40 Figure 2 is an enlarged fragmentary horizontal section taken on line 2—2 of Figure 1, with the curtains omitted for sake of clearness;

45 Figure 3 is a front elevational view of the device shown in Figure 2;

Figure 4 is a rear elevational view thereof; and

50 Figure 5 is an enlarged transverse section taken on line 5—5 of Figure 4.

55 Referring more in detail to the drawing, the present invention embodies an attaching clamp composed of a straight elongated supporting member 5 having inturned retaining and guiding flanges 6 on the longitudinal edges thereof, clamping members having flat

shanks 7 fitted and longitudinally slidable in opposite ends of the supporting member 5 beneath the guiding and retaining flanges 6 of the latter, rearwardly projecting clamping jaws 8 being provided on the outer ends of the shanks 7 for engagement with opposite sides of the upright door or window frame member 9, and the clamping jaws 8 being forcibly drawn together against the opposite sides of the frame member 9 by means of a helical tension spring 10 connecting the adjacent inner ends of the shanks 7 at the back of the supporting member 5 and midway between the flanges 6. It will thus be seen that the clamping jaws 8 may be manually forced apart against the tension of the spring 10 in accordance with the width of the frame member 9, thereby permitting application of the clamp to window frame members of different widths. The rear ends of the clamping jaws 8 are preferably provided with inwardly projecting teeth or spurs 11 adapted to bite into the sides of the frame member 9 when the jaws 8 are released and drawn together by the spring 10. The application of the clamp to wider window frame members is generally indicated by dotted lines in Figure 2.

Mounted for longitudinal adjustment on the ends of the supporting member 5 and for consequent adjustment laterally of the window or door frame, are C-shaped slides 12, which slides are also adjustable outwardly onto the outer ends of the shanks 7 when the latter are projected outwardly of the ends of the supporting member 5 for permitting engagement of the clamping jaws 8 with a relatively wide frame member 9 as indicated by dotted lines in Figure 2. As a curtain engaging and holding element 13 is carried by each slide 12, it will be apparent that the said curtain engaging or holding elements may be properly adjusted laterally of the window frame for retaining the curtains in properly drawn position at the sides of the door or window frame, irrespective of the width of the upright frame member 9 upon which the curtain holder is mounted. Each curtain engaging and holding element preferably consists of a strip of resilient sheet metal, the major intermediate portion of which is return bent to form a curtain engaging loop elongated in the direction of the supporting member 5. The inner end of the strip forming each element or loop 13 is directed rear-

wardly and laterally to form an angular supporting end 14 which is attached to the associated slide 12 so that the loop is disposed in spaced relation to the window or door frame 5 for holding the curtain out of contact with the latter as will be apparent. The laterally directed part of the angular end portion 14 is pivoted as at 15 to the associated slide 12 whereby the loop or element 13 is mounted 10 for vertical swinging adjustment as indicated by dotted lines in Figure 3, thus enabling the curtains to be held in different drawn back conditions in accordance with various desires or requirements. In other 15 words, it is apparent that by varying the position of a curtain engaging element 13 through swinging thereof in a vertical direction as indicated in Figure 3, the manner in which the curtains will be draped may be varied. 20 The outer end of the strip from which the element or loop 13 is formed is directed rearwardly as at 16 to form a closure for the inner end of the loop by engaging the inner side of the rearwardly directed part of the angular 25 end portion 14 of the strip as shown by full lines in Figure 2. In this way accidental disengagement of the curtains from the engaging element or loop 13 is effectively prevented although the outer leg of the loop may 30 be sprung outwardly as indicated by dotted lines with respect to one of the loops in Figure 2, for permitting the ready engagement of the curtain in the loop or disengagement of the curtain therefrom when desired. 35 In case it is desired to have a separate holding tape or string about the curtain, this may be done by properly looping the string and anchoring its ends to a moveable hook 17 which is held in place by friction provided 40 on the front side of the supporting member 5 intermediate its ends.

It is preferred to provide a slide 12 on each end of the supporting member 5 as shown, with a curtain engaging loop or element 13 carried by each slide, so that the device will 45 be particularly adapted for use upon an intermediate frame member of a double window frame as indicated with respect to the intermediate curtain holder of Figure 1. 50 Further, when this curtain holder is employed at the outer sides of a door or window frame as illustrated with respect to the two outer curtain holders of Figure 1, care need not be exercised in the manner in which the devices

are applied to the window frame, the inner 55 curtain engaging elements 13 being placed into service, and the outer ones of said elements 13 being allowed to simply depend as shown. However, it is within the spirit of the invention to provide either double or single curtain holders by constructing the device as shown in the several views, or by eliminating one of the slides 12 and its associated element 13.

From the above description it will be seen 65 that when the holder is placed in use, the supporting member 5 is disposed horizontally across the frame member 9 with which the holder is to be engaged, the jaws 8 being separated and positioned outwardly of the opposite sides of the frame member 9 against the tension of the spring 10. The jaws 8 are then released and the spring 10 immediately draws them tightly together into gripping engagement with the opposite sides of the frame 75 member 9. In this way the holder is securely attached in the desired position without the use of nails, screws or like fastenings. The loops 13 are then opened and the curtains are 80 engaged therein, after which the loops are adjusted laterally of the window to the desired position.

What I claim as new is:

1. A curtain holder comprising a clamp adapted for detachable engagement with the 85 upright member of a window frame and embodying a straight jaw-supporting member, jaws adjustably mounted on said jaw-supporting member, slides adjustably mounted on the ends of said jaw-supporting member 90 independently of the jaws, and oppositely projecting curtain engaging loops carried by said slides.

2. A curtain holder comprising a clamp adapted for detachable engagement with the 95 upright member of a window frame and embodying a straight jaw-supporting member, slides adjustably mounted on the ends of said jaw-supporting member, oppositely projecting curtain engaging loops carried by said 100 slides, jaws having shanks slidably mounted in opposite ends of said supporting member, and a tension spring connecting the inner ends of said shanks for normally retracting the 105 jaws.

In testimony whereof I affix my signature.

MANUEL CORREIA.
